US00D412324S

United States Patent [19] Oba

[11] Patent Number: Des. 412,324
[45] Date of Patent: ** Jul. 27, 1999

[54] INPUT MACHINE FOR COMPUTER

[75] Inventor: **Haruo Oba**, Tokyo, Japan

[73] Assignee: **Sony Corporation**, Tokyo, Japan

[**] Term: **14 Years**

[21] Appl. No.: **29/089,594**

[22] Filed: **Jun. 18, 1998**

[30] Foreign Application Priority Data

Feb. 18, 1998 [JP] Japan 10-4065

[51] LOC (6) Cl. **14-02**

[52] U.S. Cl. **D14/115**

[57] CLAIM

The ornamental design for an input machine for computer, as shown and described.

DESCRIPTION

FIG. 1 is a perspective view of a first embodiment of an input machine for computer showing my new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof;

FIG. 7 is a rear elevational view thereof;

FIG. 8 is a perspective view of a second embodiment of an input machine for computer showing my new design;

FIG. 9 is a top plan view thereof;

FIG. 10 is a left side elevational view thereof;

FIG. 11 is a front elevational view thereof;

FIG. 12 is a bottom plan view thereof;

FIG. 13 is a right side elevational view thereof; and,

FIG. 14 is a rear elevational view thereof.
